UNITED STATES PATENT OFFICE.

JOHN J. WATSON, OF SAN FRANCISCO, CALIFORNIA.

PLATEN PRESS.

Application filed November 6, 1923. Serial No. 673,068.

To all whom it may concern:

Be it known that I, JOHN J. WATSON, a citizen of the United States, residing in the city and county of San Francisco and State of California, have invented new and useful Improvements in Platen Presses, of which the following is a specification.

This invention relates to printing presses, particularly those of the platen-type.

10 Prior to my invention in the printing art, the use of type or raised cuts and the use of steel dies or engraved copper plates required the use of two entirely different types of presses. These machines being very expensive, placed a burdensome overhead on a printing establishment not having sufficient business to maintain all of the presses in continuous operation. Also, it prevented operating to full capacity on a job of one character, as only a portion of the battery of machines was adapted to that type of work.

20 With the object in view of overcoming this disadvantage, the present invention embodies a simple and inexpensive mechanism by which the operation of the present popular types of platen presses may be expeditiously changed from a machine employing type and raised cuts to a machine employing steel dies and engraved copper plates or vice-versa.

30 In carrying out this invention, I provide a wiper mechanism which may be substituted for one of the usual inking rollers. This wiper mechanism will remove the ink placed on the non-printing surfaces of the die or plate in the chase by the inking rollers and at the same time insures that ink will be supplied to the engraved or printing surfaces of the die or plate.

40 One form which the present invention may assume is exemplified in the following description and illustrated by way of example in the accompanying drawings, in which:

Fig. 1 is a perspective view of a platen-press with my improvements thereon.

45 Fig. 2 is an enlarged fragmentary view in side elevation of a platen press and disclosing certain details of construction and the manner in which my invention is applied thereto.

50 Fig. 3 is an enlarged fragmentary view disclosing the ends of the inking rollers and the wiper and showing them in position above the inking plate.

55 Fig. 4 is a fragmentary plan view of the wiper.

Fig. 5 is a cross section through the wiper showing its construction.

Referring more particularly to the accompanying drawings, 10 indicates the bed of a standard type of platen press. This bed is pivotally connected at 11 to the frame of the press so that it may be oscillated in synchronism with a platen. Such oscillation of these parts will bring them into parallelism and thereby deliver an impression from a form carried by the bed to an article to be printed carried by the platen. The bed 10 comprises vertical side members 12 and a flat transverse section 14 interposed between the side sections and which constitutes a form holder. An inking plate 15 is positioned at the upper ends of the side members above and rearwardly of the form holder. An ink fountain 16 is arranged at the upper end of the inking plate.

The ink fountain 16 and the inking plate 15 co-operate to transfer a film of ink from the fountain to the surface of inking rollers 17. These rollers are yieldably supported 80 on oscillating inking roller carriages 18 which are pivotally connected at 19 to the side members of the bed 10. The carriages 18 are oscillated by pitmen 20 and operate in timed relation with respect to the bed 10 to 85 alternately receive a film of ink and to distribute the same over the surface of a form or plate carried by the form holder 14. A reciprocable and rotatable distributing roller 21 is mounted adjacent the inking rollers 90 to aid in evenly distributing the ink over the inking surfaces of the latter.

The inking rollers 17 are fitted adjacent their ends with trucks 22 which are in contact with runways or guides 23 formed at the 95 sides of the bed 10. These runways extend along opposite sides of the form holder and the inking plate in parallelism with the working surfaces of these members.

As stated the inking rollers are mounted 100 in yieldable spring pressed bearings which maintain the trucks in contact with the runways 23. The runways act as a medium to insure that the inking rollers bear with the proper pressure on the surfaces of the 105 inking plate and the form or forms supported in the form holder 14.

The construction just described is practically standard in platen presses. As before stated, the present invention is concerned 110 particularly with certain improvements on this type of press in the nature of an attach-

ment whereby engraved plates may be used in the usual manner to reproduce the engraving as forms in lieu of the usual raised type or dies.

To accomplish this, I mount a wiping member 25 on the roller carriages 18 in parallelism with the inking rollers. The bearings 27 supporting the wiping member are movable in a direction at right angles to the longitudinal axis of the wiping member. These bearings are fitted with compression springs 28 which tend to force the wiping member toward the surfaces of the inking plate and the form holder. In lieu of a roller truck I fit each end of the wiper with a rectangular carriage 30, each of which is fitted with a pair of spaced rollers 31 which are adapted to engage the runways 23 to maintain the wiper in a predetermined relation with respect to the surfaces of the inking plate and a form in the holder 14 and to prevent the wiper from rotating.

The ends of the wiper are fitted with square shanks 29 which extend through transverse openings in the carriages 30. Adjusting screws 31^a are threaded into the carriages 30 and are collared in openings in the shanks 29 to permit the wiper to be adjusted toward and away from the surface of the form holder.

The wiper per se comprises a semi-cylindrical shell preferably of metal of appropriate thickness. A padding layer of felt 32 and an exterior covering of leather 33 are tightly stretched over the convex surface of the shell and are secured thereto by means of bail shaped clamps 34.

To prevent the wiper from contacting with the inking plate and thus receiving a charge of ink, I fix cam members 35 to the runways 23 at a point where the wiper will pass over the inking plate. These cam members simply supplement the runways to maintain the wiper from engagement with the inking plate. The length of the cam members is such as to permit the inking rollers to pass thereover and engage the inking surface of the plate.

In actual operation, the steel die or copper plate is mounted on a chase and the latter is clamped in the form holder. In case a copper plate not type high is used, I employ backing to bring it to the proper height in the chase.

On the inking stroke of the ink roller carriages, the wiper will pass downwardly over the face of the engraved plate carried by the form holder and the inking rollers will apply a film of ink to the plane or non-printing surface of the plate. On the return or upward stroke, the wiper will remove the ink from the non-printing surface and force a portion of it into the engraving to properly supply the same with ink. The bed and platen of the press will then function in the

It is desired to particularly point out that on the return stroke of the ink roller carriages the ink wiped from the plate collects in a heavy film just forward of the point where the wiper contacts with the plate. This is due to the convex surface of the wiper and results in properly supplying ink to the engraved portions of the plate.

Attention is directed to the fact that the wiper is substituted in lieu of one of the usual inking rollers. If it is desired to use type or raised cuts in the press, the wiper may be replaced by an inking roller and the cam members 35 are removed. From this and the foregoing it is obvious that by my invention, printers are enabled to employ platen presses for use in connection with type, raised cut, steel die and engraved copper plate work.

Although the present invention is disclosed as an attachment for standard designs of platen presses, it is to be understood that it may be used in connection with other designs of presses and that I do not limit myself to the form of the invention disclosed, as various changes in the construction and arrangement of the various parts may be made by those skilled in the art without departing from the invention as defined in the appended claims.

Having thus described my invention, what I claim and desire to secure by Letters Patent is:

1. In a press, an inking plate having an ink fountain, a bed having a plate holder, carriages carrying inking rollers, runways formed on the bed and engageable by trucks on said inking rollers whereby when said carriages are operated the rollers will be guided alternately over the surfaces of the inking plate and a plate in a holder in contact with the surfaces thereof to distribute ink over the surfaces of a plate in said holder, a wiper member adapted to be operated by said carriages in unison with the inking rollers, said wiper being yieldably connected to the carriages and adapted to be guided by said runways whereby it will engage and remove ink from the non-printing surfaces of a plate in said holder, and means in the path of travel of said wiper for preventing said wiper from contacting with said inking plate.

2. In a press, an inking plate having an ink fountain, a bed having a plate holder, carriages carrying inking rollers, runways formed on the bed and engageable by trucks on said inking rollers whereby when said carriages are operated the rollers will be guided alternately over the surfaces of the inking plate and a plate in a holder in contact with the surfaces thereof to distribute

ink over the surfaces of a plate in said holder, a wiper member adapted to be operated by said carriages in unison with the inking rollers, said wiper being yieldably connected to the carriages and adapted to be guided by said runways whereby it will engage and remove ink from the non-printing surfaces of a plate in said holder, and means in the path of travel of said wiper for preventing said wiper from contacting with said inking plate, said means comprising raised portions on said runways in the path of the wiper for maintaining the wiper out of contact with the inking plate, said raised portions unaffected the operation of the inking rollers.

3. In a press, an inking plate having an ink fountain, a bed having a plate holder, carriages carrying inking rollers, runways formed on the bed and engageable by trucks on said inking rollers whereby when said carriages are operated the rollers will be guided alternately over the surfaces of the inking plate and a plate in a holder in contact with the surfaces thereof to distribute ink over the surfaces of a plate in said holder, a wiper member adapted to be operated by said carriages in unison with the inking rollers, said wiper being yieldably connected to the carriages, said wiper having a convex wiping surface, roller carriages at the ends of the wiper and engageable with the runways to guide the wiper and prevent it from rotating, said wiper operable in conjunction with the inking rollers and engageable with the non-printing surfaces of a plate in said holder to remove ink therefrom, and means preventing said wiper from engaging the inking plate.

junction with the inking rollers and engageable with the non-printing surfaces of a plate in said holder to remove ink therefrom, and means preventing said wiper from engaging the inking plate.

4. In a press, an inking plate having an ink fountain, a bed having a plate holder, carriages carrying inking rollers, runways formed on the bed and engageable by trucks on said inking rollers whereby when said carriages are operated the rollers will be guided alternately over the surfaces of the inking plate and a plate in a holder in contact with the surfaces thereof to distribute ink over the surfaces of a plate in said holder, a wiper member adapted to be operated by said carriages in unison with the inking rollers, said wiper being yieldably connected to the carriages, said wiper having a convex wiping surface, roller carriages at the ends of the wiper and engageable with the runways to guide the wiper and prevent it from rotating, said wiper operable in conjunction with the inking rollers and engageable with the non-printing surfaces of a plate in said holder to remove ink therefrom, and means preventing said wiper from engaging the inking plate, said means comprising raised portions on said runways adjacent the inking plate for maintaining the wiper out of contact with the inking plate, said raised portions unaffected the operation of the inking rollers.

JOHN J. WATSON.
